UNITED STATES PATENT OFFICE.

RICHARD L. YATES, OF DAYTON, OHIO.

CENTRIFUGAL PUMP.

1,283,013.

Specification of Letters Patent. Patented Oct. 29, 1918.

Application filed October 2, 1916. Serial No. 123,421.

To all whom it may concern:

Be it known that I, RICHARD L. YATES, a citizen of the United States, residing at Dayton, in the county of Montgomery and State 5 of Ohio, have invented certain new and useful Improvements in Centrifugal Pumps, of which the following is a specification.

This invention relates to centrifugal pumps and primarily to multi-stage pumps of this 10 type.

The preferred form of the invention involves the combination in special relation of a number of features, certain of which are not individually new, the resulting structure 15 presenting a definite advance in the art in simplicity, strength and efficiency of operation as well as in ready adaptability to efficient operation under a wide range of service requirements.

20 In the preferred embodiment of the invention the casing is a simple rigid structure divided horizontally on the axis of the impeller shaft into two main parts. All water passages between stages are formed in the lower 25 or base portion of the casing, so that the joint between the two parts of the casing is a simple one, and the upper part is relatively light and readily removable to expose the shaft and impellers. This construction 30 avoids all external pipe connections between stages and reduces the number of packing glands for the shaft to two. The use of guide vanes and diffuser vanes is avoided, and instead each impeller discharges into a 35 volute chamber so formed as each to receive impellers differing in diameter and in other details of form. The impellers are of the inclosed double suction type, and thus according to their diameter project more or less 40 into the annular throat of the volute chamber. The adaptation of any particular type and size of pump to any particular service conditions within its scope is a mere question of providing it with the proper impellers. 45 The use of double suction impellers has the characteristic advantage of eliminating end thrust, and is made possible in this particular type of pump by the special arrangement of passages devised by me.

50 A four stage pump embodying the preferred form of the invention is illustrated in the accompanying drawings, in which:—

Figure 1 is a front elevation of the complete device, certain parts of the housing being broken away to show the arrangement of water passages;

Fig. 2 is a plan view of the same, the casting of the third stage being shown in section on the line 2—2 of Fig. 8;

Fig. 3 is an enlarged axial section through 60 the first and second stage casings and impellers;

Fig. 4 is a side view of an impeller with one of the inclosing shroud plates broken away to show the vanes;

Fig. 5 is a perspective view of a portion of the impeller shaft and an impeller, the upper half of the impeller being broken away to show the internal form;

Fig. 6 is an end elevation of the complete 70 pump looking from the left hand end (with reference to Fig. 1);

Fig. 7 is a transverse section through the impeller shaft, an impeller and its volute chamber on the line 7—7 of Fig. 1; and 75

Fig. 8 is a transverse section through the shaft and water passage leading from one impeller to the next, taken on the line 8—8 of Fig. 1.

The lower portion 11 of the casing or 80 housing is box-like in its general form and is provided with feet or pedestals 12 intended to be bolted to a base plate or other suitable foundation. The housing 11 carries brackets 13 and 14 to support bearing boxes 85 15 and 16 for the impeller shaft 17, the box 16 inclosing also a thrust bearing of any suitable form (not shown in the drawings) to prevent longitudinal shifting of the impeller shaft 17. The upper portion 18 of 90 the casing or housing is supported on and bolted to the lower portion 11, the plane of the joint between the two passing through the axis of the impeller shaft 17 so that the shaft is freed by the separation of the two 95 portions 11 and 18 of the housing and the removal of the caps of bearing boxes 15 and 16. The particular construction of the bearings is not a feature of the present invention and hence is not illustrated in detail. 100

The impeller shaft 17 is provided with a coupling flange 19 by which it may be connected to any suitable driving means. Near its left end it is provided with an integral collar or flange 20 and near its right end a 105 follower sleeve 21 is threaded on the shaft. Between these are assembled a series of bronze impellers 22, 23, 24 and 25 suitably spaced apart by bronze sleeves 26. The impellers are held against turning on shaft 17 by feather keys 27 and are held against axial shifting by the flange 20 follower sleeve 21 110

and sleeves 26. Since the flange 20 and follower sleeve 21 are outside the packing boxes 28 and 29, the shaft is cased in bronze throughout its length within the housing.

5 The packing boxes 28 and 29 are suited to the reception of any suitable packing (not shown) and are provided with the ordinary bolt-held followers 30 and 31. The usual water connections 32 from the discharge side 10 of adjacent impeller casings to the packing gland of each box 28 and 29 are provided, valves 33 being used to control such connections. Between the boxes 28 and 29 and between the chambers of adjacent stages the 15 shaft sleeves 26 turn in bronze or Babbitt metal bushings 34 mounted in the housing. Similar bushings 35 are provided to receive the eyes of the impellers.

The impellers are all of the inclosed double suction type, each consisting of a hub 36 of the general form shown and two annular crown or shroud plates 37 connected to the hub by spiral vanes 38. The inner openings of the crown plates 37 which form the eyes of the impellers are reinforced by annular rims 39 which turn in the bushings 35. The vanes extend from the eye to the periphery of the impeller, and the crown plates 37 are dished so as to produce, in conjunction with 20 the hub, water passages whose width decreases gradually toward the periphery of the impeller. The form of the spiral vanes and crown plates and the diameter of the impellers are all subject to change to meet particular service conditions without change in the design of any other parts of the pump, a feature of great importance in the present invention.

The housing of the pump, which as already stated, comprises two separable portions 11 and 18 is so formed as to provide impeller discharge chambers 40, 41, 42 and 43, one for each of the impellers 22, 23, 24 and 25, and pairs of suction chambers 44, 45, 46 and 47 similarly corresponding to the respective impellers. The discharge chambers 40 to 43 are substantially identical each being of the volute or "snail shell" type. The annular throats through which the impellers project into the discharge chambers are all relatively wide to permit the desired interchange of impellers. The pairs of suction chambers 44 to 47 are also substantially identical and communicate directly with the eyes of the impellers. Since the rims 39 of the impeller eyes turn in the bushings 35, a close joint is made at this point.

The intake or suction port 48 which has a connecting flange 49 leads directly to the 60 suction chambers 44 branching around chamber 40. Thence the water is thrown out through impeller 22 into chamber 40. This discharges underneath suction port 48 into a port 50 leading to the right, then upward 65 and to the rear to suction chambers 45

branching around the walls of chamber 41 to reach the chambers 45. The discharge passage from chamber 41 passes under port 50 to a port 51 which is similar to port 50 and which leads to chambers 46. The discharge passage from chamber 42 passes under port 51 to a port 52 similar to ports 50 and 51, which leads to chambers 47. The discharge from chamber 43 passes out through discharge port 53 which has a connecting flange 54. The four impellers are thus connected in series each discharging to the intake of the next through passages formed wholly in the base portion of the housing and relatively free from sudden changes of direction or cross sectional area. Any number of impellers may be similarly mounted and connected to produce any desired number of stages.

In order to prevent eddying of the water flowing in passages 48, 50, 51 and 52 the guides 55 are provided where the passages branch around the discharge chambers to direct the water to the eye of the next impeller. These are best in shown in Fig. 8.

Having thus described my invention, what I claim is:—

1. The combination of a rotatable shaft; a plurality of inclosed double-suction impellers mounted on said shaft; and a single longitudinally divided casing inclosing said impellers and formed with a volute discharge chamber for each impeller, a pair of suction chambers for each impeller, suction and discharge passages for the first and last 95 impellers respectively, and one or more branched connecting passages connecting the discharge and suction chambers of adjacent impellers, said connecting passages being formed wholly in one portion of said 100 divided casing.

2. A multi-stage pump, comprising a two-part shell or casing having formed within it a series of wide-throated volute discharge chambers, each having a pair of suction or 110 inlet passages, the outlet of each volute except the last connecting with the inlet passages of the succeeding volute chamber; a shaft extending longitudinally through said casing and having its axis in the dividing 115 plane thereof; and a plurality of independently replaceable inclosed double suction impellers carried by said shaft, one in each volute chamber, the suction or inlet passages being formed wholly within one section of 120 the casing.

3. The combination of a rotatable shaft; a plurality of inclosed double-suction impellers mounted on said shaft; and a single longitudinally divided casing inclosing said 125 impellers, and formed with a pair of suction chambers for each impeller, wide throated volute discharge chambers each adapted to receive impellers of several diameters, and suitable suction discharge and connecting 130

passages, all said passages being formed in one portion of said divided casing.

4. The combination of a rotatable shaft; a plurality of double-suction impellers 5 mounted on said shaft; and a single divided casing inclosing said impellers and formed with a volute discharge chamber for each impeller, a pair of suction chambers for each impeller, suction and discharge passages for 10 the first and last impellers respectively, and one or more connecting passages each extending from the discharge passage of one impeller longitudinally, and then branching and extending substantially radially inward 15 in the suction chambers of the next impeller.
5. The combination of a rotatable shaft; a plurality of double-suction impellers mounted on said shaft; and a single casing divided longitudinally into a base portion 20 and a cap portion, and formed with a volute discharge chamber for each impeller, a pair of suction chambers for each impeller, said base portion being provided with suction and discharge passages for the first and last 25 impellers respectively, and with one or more

connecting passages each extending from the discharge passage of one impeller longitudinally, and then branching and extending substantially radially inward to the suction chambers of the next impeller. 30

6. The combination of a rotatable shaft; a plurality of inclosed double-suction impellers mounted on said shaft; and a single casing divided longitudinally into a base portion and a cap portion, and formed with 35 a pair of suction chambers for each impeller and a wide throated volute discharge chamber for each impeller, to permit interchange of impellers differing in size, said base portion being provided with suction and discharge 40 passages for the first and last impellers respectively, and one or more connecting passages each extending from the discharge passage of one impeller longitudinally, and then branching and extending substantially 45 radially inward to the suction chambers of the next impeller.

In testimony whereof I have signed my name to this specification.

RICHARD L. YATES.
